[57] **CLAIM**

The ornamental design for a hand grip for a video camera, as shown and described.

DESCRIPTION

FIG. 1 is a top, front perspective view of a hand grip for a video camera showing our new design;

FIG. 2 is a side elevational view thereof;

FIG. 3 is a side elevational view thereof from the side opposite in that shown in FIG. 2;

FIG. 4 is a top plan view thereof;

FIG. 5 is a bottom plan view thereof;

FIG. 6 is a front elevational view thereof;

FIG. 7 is a rear elevational view thereof; and

FIG. 8 is a cross sectional view thereof taken on the line VIII—VIII of FIG. 4.
